United States Patent Office.

JOSEPH BANIGAN, OF WOONSOCKET, RHODE ISLAND, ASSIGNOR
TO THE WOONSOCKET RUBBER COMPANY.

Letters Patent No. 94,273, dated August 31, 1869.

IMPROVED APPARATUS FOR PRESSING AND VULCANIZING INDIA RUBBER.

The Schedule referred to in these Letters Patent and making part of the same.

To all whom it may concern:

Be it known that I, JOSEPH BANIGAN, of Woonsocket, in the county of Providence, and in the State of Rhode Island, have invented a new and improved Process for Pressing and Vulcanizing India Rubber; and I do hereby declare that the following is a full, clear, and exact description thereof, reference being had to the accompanying drawings, and to the letters of reference marked thereon, which make part of this specification, and in which—

Figure 1 represents a front view of my improved vulcanizing-press, the door and its flange being removed, to show the construction more clearly, and

Figure 2, a side view of the same, the interior construction being shown in dotted lines.

The object of my invention is to provide a simple and convenient apparatus for pressing and vulcanizing rubber goods, &c.; and to this end,

My improvements consist—

First, in arranging two or more plates or moulds in a heater, the upper one of which is attached to and operated by a screwed spindle passing through a shifting-box in the same.

Second, in forming the nut in which this screwed spindle works in a yoke, which yoke is connected, by two bolts, with another upon the bottom of the heater, so as to relieve the same from any pressure except that of the strain within it.

Third, in a crane and swivel for removing and replacing the door of the heater.

Fourth, in a device for causing the spindle to be rotated in only one direction when the press is in operation.

In the accompanying drawings—

A represents a metal heater, for securing the articles to be vulcanized, which receives a supply of steam by the pipes b b attached to its bottom, and rests upon feet a¹ a².

The heater contains two or more plates or moulds, B B', of suitable form, between which the articles to be vulcanized are placed.

The upper plate B' is attached to a spindle, E, which passes through a shifting-box, A¹, on the top of the heater, in such manner as to partake of the vertical but not of the rotary motion of the spindle.

This spindle has a substantial thread cut upon the upper portion of its length, which works in a nut formed in a yoke, C, above the heater.

Through openings in each end of this yoke pass the bolts D D, which extend downward through the lugs a a, on the sides of the heater, and are secured to a yoke, C, upon the bottom thereof.

The height of the yoke C, above the top of the heater, can be regulated by the nuts, d d.

By this arrangement it will be seen that the yokes

sustain the pressure when the spindle is screwed down, leaving the heater A to bear only the pressure of the steam.

To bring the required pressure upon the articles to be vulcanized, the spindle E is rotated by means of the lever E², which causes the plate B' to be moved down toward B.

The lever E² is inserted in a hole in the collar e², which is loose upon the spindle E, immediately above a collar e¹, which is firmly secured thereon.

Through openings in the two collars, a clip or catch, e, passes, extending into the collar e¹ a sufficient distance to form a fastening.

This clip is bevelled upon its lower end in such manner that when the lever E² is turned in proper direction for screwing down the plate B', it holds the collar e² fast upon the spindle, and causes a movement of rotation to be imparted thereto.

When the lever E² is turned in the opposite direction, the inclination of the lower end of the clip e causes it to be drawn out of the collar e¹, and the collar e² and lever E² then cease to give rotary motion to the spindle.

The spindle is run up when the pressure is to be taken off, by means of the hand-wheel E¹, or, if found more convenient, this wheel may likewise be used for giving the downward movement, in lieu of the lever E².

The heater is provided with a flange, a¹, around its front, to which the door A² is secured by bolts and nuts, and the joint made tight in a proper manner.

A crane, F, is pivoted to the yoke C and the top of the heater A, on which a swivel, f, moves, which is provided with a hook to which the door A² can be attached, and which can be raised or lowered by the screw f'.

A roller is attached to the swivel, in such a manner as to run on the top of the crane, for the purpose of facilitating the removal and closing of the door.

G represents a rubber cylinder which is to be vulcanized.

The operation of the press is as follows:

The article to be vulcanized being placed upon the plate B', the door A² is secured in position and made properly steam-tight.

The spindle E is then screwed down until the plate B' exerts sufficient pressure upon the articles to be vulcanized, and steam being admitted by the pipes b b, the parts are allowed to remain in this position until the operation is concluded.

The steam is then shut off, and the crane F being swung around to the front, the hook on the swivel f is inserted into a lug at the top of the door A².

The nuts which secure the door to the flange a¹ are then removed, and the door drawn out sufficiently

to clear the bolts in the flange, when the crane, being swung round, withdraws it from the opening, and the spindle E being run up by the wheel E¹, the articles are removed from the interior of the heater A.

Moulds may be substituted for the plates B B', if convenience require it.

The male part of the mould could be attached to the spindle E, which, when screwed down, would press it into the female part, resting upon the bottom of the heater.

In the case of a heavy mould, this would be found to be a decided advantage.

Having described my invention,

What I claim as new, and desire to secure by Letters Patent, is—

1. Using two or more moulds or plates in a steam-tight heater, operated from the outside thereof, substantially as described.

2. The combination of the yokes C C', bolts D D, and screwed spindle E, for the purpose of relieving the heater from pressure, as set forth.

3. The swinging crane F, and swivel f, and roller on the top of crane, for facilitating the securing and removal of the door as and for the purpose set forth.

4. The combination of the collars e¹ and e², clip e, and lever E², arranged and operating as and for the purposes set forth.

In testimony that I claim the above-described process for pressing and vulcanizing India rubber, I have hereunto signed my name, this 4th day of April, 1868.

JOSEPH BANIGAN.
